[57] CLAIM

The ornamental design for a vending machine for beverages or the like, as shown and described.

DESCRIPTION

FIG. 1 is a top front right side perspective view of a

vending machine for beverages or the like showing my new design;

FIG. 2 is a right side elevational view of embodiments 1-18 shown in FIGS. 1 and 3-19 inclusive, the left side elevational views thereof being mirror images thereof; FIG. 3 is a top front right side perspective view of a second embodiment of that shown in FIG. 1;

FIG. 4 is a top front side perspective view of a third embodiment of that shown in FIG. 1;

FIG. 5 is a top front right side perspective view of a fourth embodiment of that shown in FIG. 1;

FIG. 6 is a top front and right side perspective view of a fifth embodiment of that shown in FIG. 1;

FIG. 7 is a top front right side perspective view of a sixth embodiment of that shown in FIG. 1;

FIG. 8 is a top front right side perspective view of a seventh embodiment of that shown in FIG. 1;

FIG. 9 is a top front right side perspective view of an eighth embodiment of that shown in FIG. 1;

FIG. 10 is a top front right side perspective view of a ninth embodiment of that shown in FIG. 1;

FIG. 11 is a top front right side perspective view of a tenth embodiment of that shown in FIG. 1;

FIG. 12 is a top front right side perspective view of an eleventh embodiment of that shown in FIG. 1;

FIG. 13 is a top front right side perspective view of a twelfth embodiment of that shown in FIG. 1;

FIG. 14 is a top front right side perspective view of a thirteenth embodiment of that shown in FIG. 1;

FIG. 15 is a top front right side perspective view of a fourteenth embodiment of that shown in FIG. 1;

FIG. 16 is a top front right side perspective view of a fifteenth embodiment of that shown in FIG. 1;

FIG. 17 is a top front right side perspective view of a sixteenth embodiment of that shown in FIG. 1;

FIG. 18 is a top front right side perspective view of a seventeenth embodiment of that shown in FIG. 1;

FIG. 19 is a top front right side perspective view of an eighteenth embodiment of that shown in FIG. 1.
